UNITED STATES PATENT OFFICE.

HERMAN A. POPPENHUSEN, OF EVANSTON, ILLINOIS.

FURNACE.

1,114,803.

Specification of Letters Patent.

Patented Oct. 27, 1914.

Application filed October 24, 1910. Serial No. 588,588.

To all whom it may concern:

Be it known that I, HERMAN A. POPPENHUSEN, a citizen of the United States, and a resident of Evanston, in the county of Cook and State of Illinois, have invented certain new and useful Improvements in Furnaces; and I do hereby declare that the following is a full, clear, and exact description thereof, reference being had to the accompanying drawings, and to the letters of reference marked thereon, which form a part of this specification.

This invention relates to a furnace provided with an endless traveling grate by means of which the fuel fed to the furnace is continually advanced or moved rearwardly in a horizontally disposed layer along or through the furnace during the progress of combustion, and particularly to certain novel features of construction by means of which the air required for combustion is furnished to the fuel on the grate.

The invention consists of the matters hereinafter described and more particularly pointed out in the appended claims.

In the drawings:—Figure 1 is a longitudinal vertical section through a furnace provided with a traveling grate and having my improved construction for supplying air to the grate. Fig. 2 is a transverse section through Fig. 1 on the line 2—2 thereof. Fig. 3 is a transverse section through Fig. 1 on the line 3—3 thereof. Fig. 4 is a front elevation of the parts shown in Fig. 1.

In the drawings 10 indicates the upright side walls of the furnace; 11, the rear wall; 12, an endless traveling grate supported on sprocket wheels 13, 14, which are carried on a truck 15; and 16, truck wheels, which roll on tracks 17.

18 is the hopper.

The chain grate is made up of a plurality of plates 20 arranged in parallel, transverse rows, each plate having a downwardly projecting lug 20^a, which is made integral with a link bar 22 arranged parallel to the plate. One end of each link bar is bifurcated as shown at 22^b to receive the end of the link bar of the next succeeding plate. The ends of said link bars are provided with apertures to receive transverse rods 21 on which they are held in proper transverse spaced relation by spacing tubes 23. The plates 20 are thus arranged in longitudinal rows

which are spaced apart transversely. Between said longitudinal rows are located a plurality of longitudinally extending hollow boxes or conduits 24. In the example illustrated in the drawings there are five longitudinal rows of plates 20 and four boxes or conduits 24. Boxes or conduits 24^a, 24^b, which are half the cross-sectional area of the boxes 24, are located at each side of the grate adjacent the outer edges of the outer rows of plates 24, as plainly to be seen in Fig. 2. The boxes 24 have upright sides 24^b, 24^b, a horizontal bottom 24^c and inclined top wall sections 24^a, 24^a, which come together in the vertical plane of the longitudinal central axis of the box in the manner of a gable. The top wall sections 24^a, 24^a are each provided with openings or ports 24^e. The boxes 24^a, 24^a at each side of the chain grate have but the one inclined top section 24^a. The boxes 24 and 24^a preferably extend the length of the chain grate and are connected at their forward ends to a transverse hollow box or conduit 25 which is supported in any convenient manner on the truck frame 15. Said box 25 has a closed end 25^a and is connected at its other end to a tube or pipe 26 through which is supplied a blast of air from a fan or other suitable means (not shown in the drawings). The several boxes 24 project at their rear ends beyond the grate and are supported within suitable socket supporting plates 27 which are mounted in the rear wall 11 of the furnace. The bottom walls 27^b of the sockets 27 in said plates are preferably inclined downwardly and forwardly so as to guide the rear ends of the boxes 24 into said sockets when the grate is pushed back into the furnace after it has been withdrawn for any purpose. The side boxes 24^a, 24^b terminate short of the rear end of the grate and are supported on lugs 28 made rigid with the side frame members 15^a of the truck frame 15 (see Fig. 3).

The parts of the grate and of the boxes are so constructed and arranged with reference to each other that the lower edges of the inclined top sections 24^a of the boxes are on a level with the top of the plate 20 so that air driven through the ports or openings 24^e will strike the fuel supported on said plates near the bottom layer thereof.

The operation of the apparatus is ap-

parent from this description. Air under pressure is driven through the boxes 24, 24^a and escaping through the ports 24^b passes through the fuel from below and supports 5 combustion.

To control the supply of air escaping from the boxes I preferably provide pistons or plungers 29 which are slidably mounted in said boxes. Said pistons are connected to to 10 rods 29^a which extend lengthwise through the boxes and project through the front wall of the transverse box 25 where they are connected to a cross-bar 29^b. By moving these rods forward, portions of the box 15 at the rear may be cut off and the supply of air may thus be controlled. By the employment of the type of valve construction described and shown, the valve when operated to bring it into any position between 20 fully open and fully closed, does not diminish or reduce the supply of air to the entire conduit, as would be the case in the operation of a valve of the swinging, compression, or other type located at the mouth 25 of the conduit, or in the air supply pipe. My valve merely cuts off the air from that portion or section of the conduit in the rear of the valve, while the portions or sections of the conduit in front of the valve 30 still receive their full supply of air blast. With my type of valve construction, the blast of air may be cut off from a certain section of the fuel on the grate, while the remaining section is receiving a blast of air 35 to assist combustion. This is desirable, when the fire at the rear of the grate is burning properly and no more air, except what is supplied by natural draft is needed at this point. Other advantages will be 40 self evident to those skilled in the art to which my invention applies.

I claim as my invention:—

1. In a furnace, the combination of an 45 endless traveling grate embracing flat plates arranged in longitudinal rows spaced apart transversely, a longitudinally extending hollow conduit having a bottom wall, side walls and a top wall, said conduit being located between said rows of plates with its 50 bottom wall located below the level of all portions of said plates and its side wall spaced laterally from and out of contact with the lateral edges of said plates; the top wall of said conduit being above the 55 level of said plates and provided with at least one port or aperture, means for supporting said conduit in fixed relation to the traveling plates, and means for supplying a blast of air to said conduit.

2. In a furnace, the combination of an 60 endless traveling grate embracing flat plates arranged in longitudinal rows spaced apart transversely, a plurality of longitudinally extending conduits, each having a bottom wall, side walls and a gabled top wall com-

prising inclined sections, said conduits being located between said rows of flat plates with their bottom walls located below the level of all portions of said plates and the side walls thereof laterally spaced from and out of contact with the lateral edges of adjacent plates; the inclined sections of the top wall of each conduit projecting above the level of said plates and being provided with ports, said conduits being closed at 70 their rear ends and connected at their forward ends with a transversely extending conduit, the latter being connected with a source of air blast for supplying a blast of air to the conduits located between said 75 rows of plates, and means for supporting said conduits in fixed relation with reference to said traveling grate.

3. In a furnace, in combination, an endless traveling chain grate embracing longitudinal rows of plates spaced apart transversely, a plurality of longitudinally extending boxes located between said longitudinal rows of plates, said boxes having side and bottom walls, and a gabled top wall comprising inclined sections, said inclined sections of the top wall having ports, said boxes being closed at their rear ends and being connected at their forward ends to a transversely extending box, said transversely extending box being closed at one end and being connected at its other end to a source of air blast, means for supporting said boxes in fixed relation with reference to said traveling grate, and means for controlling said port openings embracing 90 a piston member adapted to be reciprocated in said boxes, and means for reciprocating said pistons.

4. In a furnace, the combination of an 105 endless traveling grate embracing longitudinal rows of plates spaced apart transversely, a longitudinally extending hollow conduit, having bottom, side and top walls, said conduit being located between said 110 rows of plates, the top wall of said conduit being provided with a plurality of ports or apertures, means for supporting said conduits in fixed relation to said traveling grate, means for supplying an air blast to 115 said conduit, and means for controlling the discharge of air through one or more of said ports.

5. In a furnace, the combination of an 120 endless traveling grate embodying flat plates arranged in longitudinal rows and spaced apart transversely, a plurality of longitudinally extending conduits, each having a bottom wall, side walls and a gabled top wall and provided with a plurality of ports in said top wall, said conduits being located between said rows of plates, and connected at their forward ends with a transversely extending conduit, the latter being connected with a source of air 125 130

blast for supplying air to said conduits, means for supporting said conduits in fixed relation with reference to said traveling grate, and means for controlling the discharge of air through one or more of said ports.

In testimony, that I, claim the foregoing

as my invention I affix my signature in the presence of two witnesses, this 19th day of Oct. A. D. 1910.

HERMAN A. POPPENHUSEN.
